UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

DOOR-HOLDING DEVICE.

1,421,691.

Specification of Letters Patent.

Patented July 4, 1922.

Application filed June 22, 1921. Serial No. 479,455.

To all whom it may concern:

Be it known that I, NORMAN B. HURD, a citizen of the United States of America, residing at New Britain, Hartford County, 5 Connecticut, have invented a new and useful Door-Holding Device, of which the following is a specification.

My invention relates to a holding device for swinging doors, the purpose of the same 10 being to hold the door open at an angle, so as to prevent it from being closed accidentally as by a gust of wind. Such devices are of particular utility on doors for stables and garages; where, if the door is not 15 properly held while the carriage or car is entering or leaving, said door may be swung against the car to the injury thereof.

The object of my invention is to provide certain improvements in such devices, including a novel cushioning device to prevent straining the parts should the door be rapidly opened or should the door be subjected to heavy wind pressure on either side 20 while open.

25 In the accompanying drawings I have shown my invention in a preferred form, in which—

Figure 1 is a perspective view of a portion of the door and door casing, with my 30 new holder in place, the door being held open thereby;

Fig. 2 is a plan view thereof;

Fig. 3 is a similar view of the parts when the door is closed;

35 Fig. 4 is a relatively enlarged view of the parts of the holder;

Fig. 5 is a plan view of certain portions, one of the parts being broken away;

Fig. 6 is a perspective view of certain 40 parts;

Fig. 7 is a section on the line 7—7 of Fig. 4;

Fig. 8 is a section on the line 8—8 of Fig. 5; and

45 Fig. 9 is a section on the line 9—9 of Fig. 5.

1 represents a swinging door hinged at 2 to the side 3 of the door casing. 4 represents the top of said door casing. The door holding device itself comprises a rod or bar 5, preferably of relatively thick, flat stock. This bar is hung at one end on a stud 6 carried by a bracket 7, which is secured to the door 1. Preferably the stud is on the under 55 side of the bracket so that the bar will be

normally supported at one end on the head of said stud. The stud passage through the bar is sufficiently large, and the length of the stud is such, that said bar may be easily tilted or rocked thereon on an axis extending longitudinally of the bar in the manner and for the purpose hereinafter described.

The latch and buffer mechanism is located at the free end of the bar. The latch comprises what is in effect a downwardly extending tooth 8, the edge of the tooth being beveled on the side toward the stud 6. The other edge is abrupt, to form a holding shoulder. It will be noted that this tooth is located at one side of the bar 5, so that, as the bar is rocked, the said latch tooth will rise and fall. 9 is an abutment washer mounted on the bar 5 just beyond the latch tooth 8. 10 is the base of what I may term a stationary locking abutment. This base may be secured 70 by screws to the top 4 of the door casing. One edge of this base 10 is turned downwardly and is provided with a slot or passage through which the bar 5 freely slides. The depth of the passage is sufficient to afford 75 full clearance for the latch tooth 8, while the width of said slot is sufficient to allow the rod to slide therethrough freely even when turned at an angle thereto, as shown in Figs. 3 and 4. The lower edge of the 80 slot or passage through which the bar passes is formed on an incline, as shown in Fig. 9, so that the normal locking position of the bar will be tilted somewhat.

11 is a chain, which is connected to the 85 bar between the stud 6 and the latch tooth 8. This chain hangs over the edge of the bar on the side opposite said tooth (see Fig. 4). A downward tug on the chain rocks the bar 5 on a longitudinal axis in such a manner as to lift the locking tooth 8 so that it will be disengaged from the stationary locking abutment, and may pass freely through the same.

In the preferred embodiment of my invention I employ a novel buffer construction designed to withstand shocks such as occasioned by a quick opening and stopping of the door or by quick and heavy wind pressure, and in the form shown in the drawings 105 this buffer is double-acting, so as to withstand pressure applied to either side of the door. In its most highly developed state it will be seen that this double-acting buffer requires but one spring.

In the drawings, 5^a represents an extension on the free end of the bar, the outer end of which extension is preferably threaded. 12 represents a guide pin or stud, also located on the bar, the head of the stud being on the top side on the same. 14 is a slide, which has a slot through which the guide pin 12 passes and which has a downturned lug 15 at its outer end through which the extension 5^a freely passes. In the particular form shown the abutment 9 is in the form of a plate mounted to slide on the extension 5^a. Between the lug 15 and the abutment 9 is a coil spring 16, which holds the abutment plate 9 firmly against the main body of the rod 5 at the base of the extension 5^a. 17 is a nut or stop of any suitable form on the outer end of the extension 5^a. 18 is an upstanding flange on one side edge of the slide 14. The latch tooth 8 is formed by bending downwardly the opposite side edge of the slide 14. 19 is an upstanding flange on the side of the slide 14 beyond the latch tooth 8. The forward edge of this flange 19 is preferably slightly beveled, said bevel being located in advance of the abutment 9. The abutment 9 extends above and below the slide sufficiently far so that it can never pass through the slot in the stationary abutment carried by the overhead portion 4 of the door casing.

It will be noted that the stud 12 normally stands in the forward end of the slot in the slide 14, being held in that position by the action of the spring 16, which tends to push the slide against the stop 17.

Having thus described the various parts, I will now set forth how the device operates.

If the door 1 is swung open rapidly and no effort is made to check the same manually, the rod 5 will slide rapidly through the stationary abutment until the abutment plate 9 encounters the fixed abutment. Since the abutment 9 is in reality supported by the coil spring 16, it follows that the shock will be received and cushioned by the spring through the medium of said abutment 9, the spring compressing sufficiently to relieve the shock on the parts of the holder, as well as on the door hinges. If the door is allowed to stand open and a heavy gust of wind strikes the door so as to tend to move the same in an opening direction, the buffer spring will, through the medium of the plate 55 abutment 9, operate as before, but assuming a gust of wind suddenly strikes the opposite side of the door, the buffer spring will operate to check the shock thereof, since this strain will tend to cause the bar 5 to move on the slide, carrying the abutment plate 9 with it, thereby compressing the spring, the slide itself being held against further movement in this direction by the tooth 8. During this movement the guide stud 12 moves in the slot in the slide.

By this means it will be seen that a single coil spring is capable of receiving and relieving strain on the open door in either direction.

It will be noted that while the several parts are exceedingly simple and may be very cheaply and rapidly produced, they are, nevertheless, few in number and of such design as to possess great durability. They likewise are capable of being assembled very easily.

While I have shown the invention in its preferred form, manifestly various changes and modifications may be made without departing from the spirit of the invention or the scope of the following claims.

What I claim is:

1. A door holder comprising, a bar adapted to be pivotally connected at one end to a door, said bar being rockable on its own longitudinal axis, an abutment having a passage therethrough for said bar and adapted to be carried by an overhead portion of a door casing, a latch device on said bar at one side of the longitudinal axis of the same and arranged to detachably engage a portion of said stationary abutment when said bar is in one position, a buffer device, and means for rocking said bar on its longitudinal axis to disengage said latch from said stationary abutment whereby said rod may be moved longitudinally through the abutment passage.

2. In a door holder, a rod adapted to be secured at one end to a door, a stationary abutment having a passage therethrough for said rod, said abutment being adapted to be secured to the overhead portion of a door casing, a latch for inter-engaging said rod with said abutment when the door is open, and a single double-acting buffer spring co-operating directly with said latch and bar.

3. In a door holder, a rod adapted to be secured at one end to a door, with means for rocking the same on its longitudinal axis, a latch tooth at one side of said bar near the other end, a stationary abutment having a slot therethrough of adequate size to permit said tooth to pass therethrough, a movable abutment plate arranged to co-act with said tooth to engage said stationary abutment, and a buffer spring co-operating with said parts to receive and cushion endwise shocks on the same in both directions.

4. In a door holder, a rod, means for supporting the same at one end and for connecting the same to a door, said means permitting said rod to rock on an axis extending longitudinally thereof and to swing in a horizontal plane with relation to the door, with latch mechanism at the free end of said rod, a double-acting buffer co-acting directly with said latch mechanism, and means comprising a stationary abutment arranged to be secured to the overhead part of the door

casing and co-acting with said latch and said buffer.

5. In a door holder, a rod adapted to be secured at one end to a door and to tilt on a longitudinal axis, a slide mounted on the free end of the rod and having a latch tooth at one side edge thereof, said slide having a limited amount of longitudinal movement relatively to said rod, an abutment carried 10 by said rod and slidable thereon, a spring interposed between said abutment and said slide, said spring operating to permit said abutment to move under restraint in one direction relatively to said rod and slide and 15 permitting said slide to move under restraint in an opposite direction relatively to said rod and abutment, and a relatively stationary abutment adapted to be secured to a door casing and arranged to co-act with 20 said rod, tooth and movable abutment, said stationary abutment having a passage therethrough of sufficient size to permit said rod and tooth to slide therein and therethrough, said movable abutment being of such a size 25 as to be incapable of passing through said passage.

6. In a door holder of the character described, a rod, means for securing the same at one end to a door, said means being constructed to permit said rod to be rocked on a longitudinal axis and to be swung with

relation to the door, a latch at the opposite end of the rod comprising a downwardly-projecting tooth at one side of the rod, an abutment carried by the rod and co-acting 35 with said tooth, a stationary abutment arranged to be secured to the overhead part of a door casing and having a passage therethrough for the rod and tooth, said abutment being engaged between said tooth and the 40 abutment when the door is opened, and a buffer co-acting with said parts to cushion in both directions endwise strain on the rod.

7. In a door holder of the character described, a rod, means for securing the same 45 at one end to a door, said means being constructed to permit said rod to be rocked on a longitudinal axis and to be swung with relation to the door, a latch at the opposite end of the rod comprising a downwardly- 50 projecting tooth at one side of the rod, an abutment carried by the rod and co-acting with said tooth, a stationary abutment arranged to be secured to the overhead part of a door casing and having a passage therethrough for the rod and tooth, said abutment being engaged between said tooth and the 55 abutment when the door is opened, and a buffer co-acting with said parts to cushion in both directions endwise strain on the rod, 60 said buffer comprising a single coil spring.

NORMAN B. HURD.
